PARTING FLANGE OR DIVIDER FOR
DRILLING DRUMS

William Cary Sole, Bristow, Okla.

Application March 31, 1938, Serial No. 199,242

6 Claims. (Cl. 242—117)

This invention relates to dividers which are mounted on the drums of well drilling machines for the purpose of separating the reserve portion of the cable from that portion thereof which is, for a time at any rate, in constant use. From time to time as the drill goes deeper into the well, it is necessary to pull the tools from the bottom and to take off one turn of cable from the reserve end of the drum, cross it over the divider and shift this turn of the cable to the active portion of the drum. To this end, dividers are usually formed in two sections held to the shaft or drum by bolts and in taking off a turn of the reserve cable from the reserve portion of the drum, it is necessary to cross the cable over one of said bolts that holds the divider to the shaft of the drum. This is likely to make short bends or crooks in the cable which will weaken the cable and make it break very readily, leaving the tools in the bottom of the well. Furthermore, in constructions of this character, the bolts that hold the divider to the shaft or drum are so placed that the weight of the cable and of a heavy string of drilling tools is very likely to break the bolts which hold the divider to the shaft. Furthermore, inasmuch as the ends of the bolts stick out through the divider, these bolt ends will often catch in a man's clothing and cause injury to the operator.

The general object of the present invention is to avoid the difficulties heretofore mentioned and particularly to provide a divider in which the cable does not have to be passed over any bolts in order to cross it from one side of the divider to the other but in which the divider is so formed that the cable is guided gently from the reserve portion of the drum onto the periphery of the divider and then as gently guided onto the active portion of the drum without passing over any bolts or other portions of the divider which would catch, bend or kink the cable.

Another object is to provide a divider on the order of a pulley with the cable going entirely around the divider and assisting in pressing the divider tight onto the shaft or drum.

A further object is to provide a divider of this character which will leave the cable straight and without kinks or bends.

Other objects will appear in the course of the following description.

My invention is illustrated in the accompanying drawing wherein:

Fig. 1 is a fragmentary elevation of an oil well drum and derrick showing my separating flange applied thereto.

Fig. 2 is an edge elevation of the flange or separator partly broken away.

Fig. 3 is a side elevation of the separator partly broken away.

Fig. 4 is a fragmentary section on the line 4—4 of Fig. 3.

Referring to the drawing, 10 designates the drum of a drilling machine, this drum having a large portion 11 and a smaller diametered portion 12. The cable 13 which is used in drilling is taken from the small portion of the drum and from that end which is remote from the large diametered portion of the drum.

Separating the large diametered portion of the drum from the small diametered is the divider 15 such as heretofore described. This divider, as shown in Fig. 3, is in the form of a pulley having a hub portion 14 which may embrace the drum itself or be mounted upon the shaft of the drum and having the lateral flanges 15 and 16, which define between them the circumferential groove 17. The flanges 15 and 16 extend almost continuously around the pulley-like divider but at one point each of these flanges is formed with a substantially radial and relatively wide slot 18. The slot in one side wall 15, for instance, is exactly opposite the slot in the other side wall 16 and extending diagonally across this open portion of the divider and diagonally with relation to the side walls 15 and 16, there is a diagonal wall 19 which merges at one end into the wall 15 and at its other end into the wall 16, so as to form a diagonal passage leading from the side of the divider into the groove 17 and from this groove out to the opposite side face of the divider. Guide grooves 20 extend from each one of these openings 18 in a direction circumferentially and toward the hub of the wheel, these guide grooves gradually getting shallower as they extend away from the opening 18. Each of these guide grooves is substantially tangential to the central opening of the hub portion 14.

Apertures 21 may extend through the hub or solid portion of the divider for the sake of making the divider relatively light. These apertures 21 may have any desired form but, as shown, are radial to the center of the divider.

The divider is preferably formed in two sections, the sections being cut on the line 22 in Fig. 3. The sections are formed with confronting recesses 23 which, when the sections are together, form transversely extending slots through the hub portion of the divider and extending from one section into the other are a pair of tightening bolts 24. These bolts extend across

55

the openings 23 and have screw threads at their opposite ends of opposite hand. These screw threads engage with nuts 25 having screw threads of opposite hand, these nuts being disposed within bores 26. These nuts may be held from rotation in any suitable manner and, as illustrated in Fig. 2, these nuts consist of transversely extending rods extending through from one face of the divider to the other, these rods 10 being many-sided in cross-section and having screw threaded bores which in effect constitute nuts. It will be obvious that the bolts may be rotated to disconnect the sections or rotated in the opposite direction to draw the sections 15 toward each other and clamp the sections tight upon a shaft or drum.

It will be seen that the bolts 24 are entirely enclosed within the divider and do not project in any way where they can either act to kink or 20 bend a cable or where they become dangerous to an operator. It will be also seen that the cable 13 will go entirely around this pulley-like divider and that it will act to press the two sections of the divider tight against the shaft or drum. In 25 crossing in this manner, the cable goes over the bolts and takes all strain off the bolts and at the same time the cable is kept straight and without any kinks or bends in it. Inasmuch as the cable supports a heavy string of drilling tools, it is important that the cable shall not touch the bolts or 30 not act to break the bolts that hold the divider to the shaft.

While I have illustrated a particular embodiment of my invention which I believe to be particularly effective, I do not wish to be limited to this as it is obvious that many changes might be made without departing from the spirit of the invention as defined in the appended claims.

What is claimed is:

- 40 1. A cable divider for drums or shafts, comprising a centrally apertured disk-like element having means for clamping it on a drum or shaft, the element being formed to provide a peripheral groove defined by two lateral walls spaced to receive only a single turn of cable, the lateral walls of the groove being provided with axially spaced slots, a guiding wall disposed obliquely of and between the lateral walls and joining the remote edges of the said slots.
- 45 2. A cable divider for drums or shafts, comprising a centrally apertured disk-like element having means for clamping it on a drum or shaft, the element being formed to provide a peripheral groove extending entirely thereabout, and defined by two lateral walls spaced to receive only a single turn of cable, the walls of the groove being provided with axially spaced slots and there being a guiding wall disposed between the said slots in the lateral walls of the groove, the guiding wall extending diagonally across the groove and at one end merging into one lateral wall at one end of a slot and at its other side merging into the other lateral wall at the side of its slot remote from the said side of the other slot, the hub portion of the disk-like element having shallow grooves upon the side faces each extending from a slot, the grooves extending tangentially to the aperture in the center of the divider and growing gradually shallower outward from the slot, the grooves extending in opposite directions from and in the plane of the diagonal wall.
- 50 3. A divider of the character described, having the general form of a pulley provided with a medial encircling groove and two lateral walls bordering the groove, said groove being formed

to take a single turn only of a cable, the walls having radial slots extending to the bottom of the groove, the slots being axially spaced from each other, and means extending diagonally across the groove and located at said slots whereby to guide a cable gently into one of said slots and into the groove and guide an opposite portion of the cable out of said groove and through the corresponding slot in an opposite direction to that portion of the cable entering the groove.

4. A cable divider for well drilling drums or shafts having the form of a pulley provided with a hub portion, a peripheral groove and two lateral walls defining said groove, said groove being formed to take only a single turn of cable, said lateral walls at one point being radially slotted to the bottom of the groove, the slots having a width equal to the width of the groove and being axially oppositely disposed, a diagonally extending guiding element projecting radially outward from the periphery of the groove and extending obliquely across the groove between remote sides of said slots to guide a cable into the groove and out of the groove after the cable has made a single complete turn around the divider in the peripheral groove thereof, the divider being formed in two sections, and means whereby the sections may be drawn towards each other for clamping upon a shaft or drum or expanded with relation to each other, said clamping means being disposed entirely within the hub portion of the divider.

5. A cable divider for well drilling drums or shafts having the form of a pulley provided with a hub portion, a peripheral groove and two lateral walls defining said groove, said groove being formed to take only a single turn of cable, said lateral walls at one point being radially slotted to the bottom of the groove, the slots having a width equal to the width of the groove and being axially oppositely disposed, a guiding element projecting radially outward from the periphery of the groove and extending obliquely across the groove between remote sides of said slots to guide a cable into the groove and out of the groove after the cable has made a single complete turn around the divider in the peripheral groove thereof, the divider being formed in two sections, means whereby the sections may be drawn towards each other for clamping upon a shaft or drum or expanded with relation to each other, said clamping means comprising a pair of screws disposed one on each side of the central opening of the divider, each screw having screw threaded portions at its ends of opposite hand, and nuts disposed in the hub of the divider with which said screw threaded portions engage, the hub of the divider having axially extending openings through which access may be had to the screws to rotate them.

6. A cable divider for well drilling drums or shafts having the form of a pulley provided with a hub portion, a peripheral groove and two lateral walls defining said groove, said groove being formed to take only a single turn of cable, said lateral walls at one point being radially slotted to the bottom of the groove, the slots having a width equal to the width of the groove and being axially oppositely disposed, a guiding element projecting radially outward from the periphery of the groove and extending obliquely across the groove between remote sides of said slots to guide a cable into the groove and out of the groove after the cable has made a single complete turn around the divider in the peripheral groove thereof, the

divider being formed in two sections, means whereby the sections may be drawn towards each other for clamping upon a shaft or drum or expanded with relation to each other, said clamping means comprising a pair of screws disposed one on each side of the central opening of the divider, each screw having screw threaded portions at its ends of opposite hand, and axially extending many-sided elements passing trans-

versely through the hub of the divider on each side of the line dividing the two sections, each element being internally screw threaded for engagement by the threads on the said screws, the hub of the divider having axially extending openings through which the screws pass and by which access may be had to the screws to rotate them.
